(57) **CLAIM**

The ornamental design for an upgradeable multimedia module connector, as shown and described.

DESCRIPTION

FIG. 1 is a front, top and left side perspective view of the male portion of an upgradeable multimedia module connector showing our new design;

FIG. 2 is a front, bottom and left side perspective view thereof;

FIG. 3 is a right side elevation view thereof. The left side elevation view is a mirror image thereto;

FIG. 4 is a top plan view thereof;

FIG. 5 is a front elevation view thereof;

FIG. 6 is a bottom plan view thereof;

FIG. 7 is a rear elevation view thereof;

FIG. 8 is a front, top and left side perspective view of the female portion of an upgradeable multimedia module connector showing our new design;

FIG. 9 is a front, bottom and left side perspective view thereof;

FIG. 10 is a right side elevation view thereof. The left side elevation view is a mirror image thereto;

FIG. 11 is a top plan view thereof;

FIG. 12 is a front elevation view thereof;

FIG. 13 is a bottom plan view thereof; and,

FIG. 14 is a rear elevation view thereof.
